J. R. BUCHANAN.
WHEELED CHAIR SUPPORT.
APPLICATION FILED AUG. 4, 1915.

1,189,053.

Patented June 27, 1916.

UNITED STATES PATENT OFFICE.

JOHN R. BUCHANAN, OF WAUKESHA, WISCONSIN.

WHEELED-CHAIR SUPPORT.

1,189,053.

Specification of Letters Patent. Patented June 27, 1916.

Application filed August 4, 1915. Serial No. 43,656.

To all whom it may concern:

Be it known that I, JOHN R. BUCHANAN, a citizen of the United States, residing at Waukesha, in the county of Waukesha,

5 State of Wisconsin, have invented certain new and useful Improvements in Wheeled-Chair Supports; and I do declare the following to be a full, clear, and exact description of the invention, such as will enable 10 others skilled in the art to which it appertains to make and use the same.

This invention relates to new and useful improvements in wheeled supports and is particularly directed to the provision of 15 such a support for chairs.

The various types of rolling chairs designed for use of invalids present a serious inconvenience in that they are of such size as to prove cumbersome in use in an ordinary household, and it is therefore the object of the present invention to provide a wheeled device for the use of invalids which is of such design that it will not prove cumbersome and permit free passage through 25 doorways.

It is further an object of the invention to provide such a device which may have associated therewith as a part thereof a chair of conventional type.

30 It is still further an object to provide such a device which is exceedingly simple in structure so as to prove durable and efficient in continued use, and to permit manufacture thereof at a comparatively low cost consistent with such durability and efficiency.

With the above and other objects and advantages in view, the invention resides more particularly in the novel combination, formation and arrangement of parts as more 40 fully described and pointed out in the appended claims.

Reference is had to the accompanying drawings, wherein similar characters of reference designate corresponding parts 45 throughout the several views, and in which:

Figure 1 is a perspective view of the improved device. Fig. 2 is a sectional view taken on the line 2—2 of Fig. 1. Fig. 3 is a top plan view of the device. Fig. 4 is a 50 perspective view of one corner of the device showing the modified means for holding the chair legs.

Referring now more particularly to the accompanying drawings, the improved device is shown as comprising a frame formed 55 of the side sills 5 and the end sills 6 which

are crossed and which are formed at their crossing with grooves 7 forming a dowel joint 8. A wheel support for this frame comprises casters 9 preferably of a conventional ball-bearing type which are secured at the corners of the frame by fastening their attaching plates 10 of each caster to both of the sills forming the joint. Thus the strain on the sills is distributed and 60 additional means provided for securing the joints together, the primary means for such securement comprising screws 11 passed through the joints.

The frame is braced by triangular plates 12 secured on the corners thereof, and to secure a chair 13 of the usual type on the device, the ends of the transverse sills 6 are provided with sockets 14 seating the legs of the chair. If the chair is relatively small, 75 securing sockets therefor may be provided in the plates 12 as designated at 14'.

To provide a draft attaching means for the device positioned sufficiently outwardly of the front thereof to promote efficient operation, and at the same time to provide a foot rest, the side sills 5 are extended and inclined upwardly at 15, and a foot board 16 has its ends seated in a cutaway portion 17 in the top thereof and secured. These 80 extended portions 15 carry eyes 18 with which may be associated any desired draft means.

In Fig. 4 is shown a modified form of the device wherein the legs of the chair seat in 90 socket members 19 which carry laterally extending arms 20 at their ends which are secured on the sills. In this form of the device illustrated, some adjustment is had for different sizes of chairs, as the relative position of these socket members may be 95 varied.

From the foregoing it is observed that an exceedingly simple device has been provided with which may be associated a chair of conventional type to form a wheeled chair particularly adapted for use of invalids and which may be readily and conveniently moved about and passed through doorways.

100 While I have illustrated and described a particular embodiment of my invention, I have merely done so for the sake of convenience and I do not wish to be limited to that particular embodiment as it is obvious that numerous changes may be made within the 105 details of construction thereof without in any way departing from the spirit of the 110

invention or exceeding the scope of the appended claims.

What I claim is:—

- 5 1. A device of the class described comprising a bottom frame, said frame being provided at each corner with a plurality of sockets extending downward from the top thereof and having their centers disposed on diagonal lines extending from corner to corner of the frame, wheeled supporting means for said frame and a foot plate carried by the frame in front thereof.
- 10 2. A device of the class described, together comprising side and end sills connect-

ed to form a rectangular frame, substantially triangular bracing plates at each corner of the frame and secured to the side and end sills to hold the frame against distortion, each of said bracing plates being provided with a plurality of leg receiving sockets; and wheeled supporting means for said frame.

In testimony whereof, I affix my signature, in the presence of two witnesses.

JOHN R. BUCHANAN.

Witnesses:

E. W. JUNEMANN,
L. J. FEDERER.
